UNITED STATES PATENT OFFICE.

JULES MÉLOTTE, OF REMICOURT, BELGIUM.

CENTRIFUGAL LIQUID-SEPARATOR.

SPECIFICATION forming part of Letters Patent No. 734,585, dated July 28, 1903.

Application filed September 12, 1902. Serial No. 123,068. (No model.)

To all whom it may concern:

Be it known that I, JULES MÉLOTTE, a subject of the King of Belgium, residing at Remicourt, Belgium, have invented certain new and useful Improvements in Centrifugal Separators for Liquids; and I do hereby declare the following to be a full, clear, and exact description of the invention, such as will enable others skilled in the art to which it applies to make and use the same, reference being had to the accompanying drawings, and to letters of reference marked thereon, which form a part of this specification.

As is well known, the arrangement within the drums of centrifugal separators—such as centrifugal milk-separators, for example—of inclined walls or partitions dividing the liquid to be separated into sheets and cutting the radius of the drum facilitates the separation of the constituent parts of different densities. The partitions which are employed to this end are either concentric or eccentric to the axis of rotation of the drum. In the case of concentric partitions the latter may be of various forms, such as conical, zigzag, undulating, &c. They are superposed within the drum and are situated in a vertical plane or a horizontal plane, accordingly as the drum may be rotated in one or the other of such planes. In cases in which the partitions are eccentric they are arranged at right angles or practically at right angles to a vertical plane or a horizontal plane, accordingly as the drum may be rotated in one or the other of such planes, and are composed of wings or blades, which may be of plane, undulating, zigzag, partially-spiral, or other suitable form. It is only necessary in order that these partitions may facilitate the separation of the cream that they shall not coincide with the radius, but intersect it. Whatever may be their form or their position in the drum it is necessary in order that these partitions may produce a sufficient marked effect upon the separation that they shall be sufficient in number, and all forms of such apparatus as hitherto constructed require the expenditure of much time for dismounting, cleaning, and reassembling. In order to facilitate the dismounting, it is only necessary to connect the parts at the axis; but this arrangement does not permit of the employ-

ment of a large number of blades, because cleaning them would be rendered difficult if not impossible. The arrangement which forms the subject of this invention serves to obviate these defects.

In the accompanying drawings, Figure 1 is a vertical section of one form of the improved separator. Fig. 2 is a plan of the same. Fig. 3 is a sectional elevation of one series of blades on the line G H of Fig. 4. Fig. 4 is a plan of the same. Fig. 5 shows the drum mounted within a casing and illustrates the manner of using the same.

In carrying out the invention I insert within the usual drum a set of connected blades A, Figs. 3 and 4, the number of the blades in a set being sufficiently small to present no obstacle to cleaning; but instead of connecting the blades or partitions composing this set one with the other throughout their entire height I only connect them for a portion of such height, as at D, Fig. 3, so that the remaining portion E (about three-quarters of the whole height) may be free, leaving a greater or less interval or space between the axis F and the free inner edges of these blades, which gives the form shown in Figs. 3 and 4. In other words, the partitions in the set are well separated, except at or near their lower extremities, so as to form a central vertical recess or clearance E in the set. I then arrange in the same manner a second series, as at B, Fig. 1, only instead of the point of connection D being as in the first part I arrange it at another point in the height—as at D', Fig. 1, for example. Obviously this second part may be arranged in a drum within which the first part has already been mounted, the blades of each of these two parts being interposed between each other, while the points of connection are superposed. In other words, the partition-connecting members D' in this set occupy a position within the recess E of the first-mentioned set. Said connecting members D' are, however, of no greater height or width than is desirable for effecting a suitable connection, so that the upper portion of the recess E still remains unoccupied, although eight partitions are assembled. In this manner a still larger number of these sets may be arranged within a drum, it being only necessary that the points of connection of the blades

in one set shall not coincide as to height with the connections in any other set. In Figs. 1 and 2 I have shown three of these sets of blades. Instead of soldering the blades in each set directly one to the other they may be connected in any other suitable manner, as by the intermediary of connecting parts, such as hubs, star-shaped pieces, and the like.

It will be understood that owing to the infectious nature of a single drop of impure milk it is essential to give the separator frequent and thorough cleansing. It has heretofore been considered an objection to the use of numerous vanes or partitions within the drum, that they are difficult of access for the purpose of cleaning, and besides they present numerous crannies and other openings in which drops of impure milk are likely to become secreted, so that they are difficult to cleanse. My invention, it will be seen, enables the use of any number of partitions and avoids this objection, since the entire group of partitions may be divided into as many units as desired, each unit consisting of two or more well-separated partitions, which may be assembled or nested with the remaining units and subsequently may be lifted out one at a time and cleansed with great facility, every part of each unit being easily accessible and the drum itself being also left open and free of access.

It will be seen that the unit illustrated at Fig. 4 consists of a set of partitions fastened together at their inner edges and that this unit is adapted to nest with other units, as B and C, Figs. 1 and 2, the partitions in one unit alternating with those in another unit and the connections, as D and D', being diversified to permit the nesting of the units. The partitions preferably converge and may be of various forms within the scope of my invention. Preferably the partitions are rigidly connected, the connections being either integral or otherwise. It will be understood that the partitions in one unit may be connected at their lower ends and those in another unit at their upper ends, while those in still other units may be connected at their middle portions, and all may be nested in a drum, as seen in Figs. 1 and 2. The partitions in each unit are preferably discrete, being separated for the accommodation of the connecting members of other units.

At Fig. 5 it will be noted that the drum B' may be formed of lower and upper sections b and b', fitted together and held by means of a threaded hoop A', and it will be understood that the usual packing (not shown) may be inserted between the edges of the drum-sections. The drum is suspended by means of a hook Z upon a vertical revoluble shaft D'', which latter may receive its rotary movement from a belt or in any other usual manner. The drum is suspended upon the hook Z by means of an eye Z', whereby the drum is caused to rotate, but is permitted to swing slightly. Said eye Z' is formed with a shank

Z², which is secured to an inverted yoke Z³, the ends of which are secured at Z⁴ within and to the roof of the drum. Milk is fed into the drum through a spout T and is received by a bowl G, which is supported by a central thumb-nut G' upon a threaded stud G², dependent from the shank Z², the rim of the bowl preferably contacting with the roof of the drum. The milk flows from the spout T into the bowl G, which becomes filled, and is distributed therefrom through openings O into the drum B', as indicated by the arrows. The partitions A, B, and C facilitate the separation of the constituents of the milk into two bottles, according to the order of their specific gravities. The separated milk being the heavier collects at the concave part of each partition, while the cream collects at the convex part thereof, and on account of the differences in the specific gravities the cream forms an inner body at the axis of the drum, while the separated milk passes to the outer wall of the drum. The cream passes down through a central outlet T', depending from the floor of the drum, and falls into a basin T², from which it flows out through a spout M. The separated milk, which flows to the side walls of the drum, escapes down past the edge of a false floor F', provided in the drum, and passes beneath the same through an outlet P at the bottom of the drum and escapes therefrom into a basin E², formed in a casing E', in which the drum is placed, from whence it escapes through a spout N, all as indicated by the arrows.

Having now particularly described and ascertained the nature of my said invention and in what manner the same is to be performed, I declare that what I claim is—

1. A nest of partitions for the drum of a centrifugal separator, said nest comprising a plurality of units, each unit consisting of a set of partitions, and means for connecting them together, the partitions in one unit intervening between those in another unit, and the connecting means of one unit being at a different height from the connecting means of another unit, to permit nesting of the units.

2. A nest of partitions for the drum of a centrifugal separator, said nest comprising a plurality of units, and each unit consisting of a set of partitions provided with connections, the connections in one set being at a different height from the connections in another set, and the partitions in one set intervening between the partitions in another set.

3. A nest of partitions for the drum of a centrifugal separator, said nest comprising a plurality of units, one unit consisting of a set of partitions rigidly connected at their lower portions, and another unit consisting of a set of partitions rigidly connected at their upper portions; the partitions in one set intervening between those in another set.

4. A nest of partitions for the drum of a centrifugal separator, said nest comprising a plurality of units; one unit consisting of a set of

partitions rigidly connected at their lower portions; and another unit consisting of a set of partitions rigidly connected at their upper portions; the partitions in one set intervening between those in another set.

5. A nest of partitions for the drum of a centrifugal separator, said nest comprising a plurality of units; one unit consisting of a set of partitions rigidly connected at their lower portions; another unit consisting of a set of partitions rigidly connected at their upper portions; and another unit consisting of a set of partitions rigidly connected at their middle portions; the partitions in one unit intervening between those in another.

6. A set of discrete partitions rigidly connected only at the bottom, for insertion within the drum of a milk-separator.

7. A set of discrete partitions connected only at their middle portions, for insertion within the drum of a milk-separator, and adapted for use in nesting with other sets which are connected at the bottom.

8. A nest of converging partitions for the drum of a centrifugal separator, said nest comprising a plurality of units, and each unit consisting of a set of partitions fastened together at their inner edges, the partitions in one unit intervening between those in another unit, and the connections being at different heights, to permit nesting of the units.

9. A nest of converging partitions for the drum of a centrifugal separator, said nest comprising a plurality of units, and each unit consisting of a set of partitions provided at their inner edges with connections, the connections in one set being at a different height from the connections in another set, and the partitions in one set intervening between the partitions in another set.

10. A nest of converging partitions for the drum of a centrifugal separator, said nest

comprising a plurality of units, one unit consisting of a set of partitions rigidly connected at the lower portions of their inner edges, 45 and another unit consisting of a set of partitions rigidly connected at the upper portions of their inner edges; the partitions in one set intervening between those in another set.

11. A nest of converging partitions for the drum of a centrifugal separator, said nest comprising a plurality of units, one unit consisting of a set of partitions rigidly connected at the lower portions of their inner edges; and another unit consisting of a set of partitions rigidly connected at the upper portions of their inner edges; the partitions in one set intervening between those in another set.

12. A nest of converging partitions for the drum of a centrifugal separator, said nest 60 comprising a plurality of units, one unit consisting of a set of partitions rigidly connected at the lower portions of their inner edges; another unit consisting of a set of partitions rigidly connected at the upper portions of 65 their inner edges; and another unit consisting of a set of partitions rigidly connected at the middle portions of their inner edges; the partitions in one unit intervening between those in another.

13. A set of converging discrete partitions connected only at the middle portions of their inner edges, for insertion within the drum of a milk-separator, and adapted for use in nesting with other sets which connect at their 75 bottom portions.

In testimony that I claim the foregoing as my invention I have signed my name in presence of two subscribing witnesses.

JULES MÉLOTTE.
